[57] CLAIM

The ornamental design for combined perfume bottle and closure, as shown and described.

DESCRIPTION

FIG. 1 is a right side elevational view of a combined perfume bottle and closure showing my new design; FIG. 2 is a rear elevational view thereof; FIG. 3 is a top plan view thereof; FIG. 4 is a bottom plan view thereof; FIG. 5 is a front perspective view thereof, the closure removed for clarity of illustration; FIG. 6 is a front perspective view of FIG. 1; FIG. 7 is a top plan view of FIG. 5; FIG. 8 is a front perspective view of the stopper shown separately for clarity of illustration; FIG. 9 is a bottom plan view of FIG. 8; FIG. 10 is a front elevation view of a second embodiment of FIG. 1, the only difference being the bottle and closure are transparent; FIG. 11 is a left side elevational view of FIG. 10; FIG. 12 is a front perspective view of a third embodiment of FIG. 1, the only difference being the closure and bottle neck are threaded; FIG. 13 is a front perspective view of FIG. 12, the closure removed for clarity of illustration; FIG. 14 is a top perspective view of FIG. 13; FIG. 15 is a front perspective view of the closure shown separately for clarity of illustration; FIG. 16 is a bottom plan view of FIG. 15; FIG. 17 is a right side elevational view of a fourth embodiment of FIG. 1, the only difference being the bottle and closure are transparent and the closure and bottle neck are threaded; FIG. 18 is a rear elevational view of FIG. 17.
